(57) CLAIM

The ornamental design for a single-sole shoe with purple stripe and purple sole, as shown and described.

DESCRIPTION

The file of this patent contains at least one drawing executed in color. Copies of this patent with color drawing(s) will be provided by the Office upon request and payment of the necessary fee.

FIG. 1 is a perspective view of a single-sole shoe with purple stripe and purple sole shaded to show the color Purple, showing our new design;

FIG. 2 is a first side view thereof;

FIG. 3 is a second side view thereof;

FIG. 4 is a top view thereof;

FIG. 5 is a bottom view thereof;

FIG. 6 is a front view thereof;

FIG. 7 is a rear view thereof;

FIG. 8 is a perspective view of a second embodiment of our new design of a single-sole shoe with purple stripe and purple sole, where the Purple portions are indicated using the USPTO convention of broken vertical lines for Purple;

FIG. 9 is a first side view thereof;

FIG. 10 is a second side view thereof;

FIG. 11 is a top view thereof;

FIG. 12 is a bottom view thereof;

FIG. 13 is a front view thereof; and,

FIG. 14 is a rear view thereof.

The broken lines illustrating the channel on the Purple sole and the half-moon in the above depict unclaimed environmental subject matter.
